UNITED STATES PATENT OFFICE.

GEORGE A. GEMMER, OF DETROIT, MICHIGAN, ASSIGNOR TO GEMMER-DETROIT STARTER CO., OF DETROIT, MICHIGAN, A CORPORATION OF MICHIGAN.

PNEUMATIC STARTER FOR INTERNAL-COMBUSTION ENGINES.

1,129,661.

Specification of Letters Patent.

Patented Feb. 23, 1915.

Application filed February 16, 1914. Serial No. 818,901.

To all whom it may concern:

Be it known that I, GEORGE A. GEMMER, a citizen of the United States, residing at Detroit, in the county of Wayne and State of Michigan, have invented a new and useful Improvement in Pneumatic Starters for Internal-Combustion Engines, of which the following is a specification.

My invention relates to an improvement 10 in pneumatically-operated means for starting the internal-combustion engines of automobiles, motor-boats, and the like; and my primary object is to provide for the purpose mechanism rendered very simple 15 in construction by employing a type of valve peculiarly adapted thereto in serving to cause a supplemental engine to be operated by the internal-combustion engine as a pump for compressing air and storing it, 20 and to cause the stored air to operate the supplemental engine as a motor for starting the internal-combustion engine.

In the accompanying drawings, Figure 1 is a view in side elevation, partly broken and 25 sectional, of my improved device; Fig. 2 shows the same by a plan view and Fig. 3 by a view in end elevation; Fig. 4 is a section on line 4 of either Fig. 2 or Fig. 3; Fig. 5 is an enlarged section on line 5, of Fig. 1, Fig. 30 7 or Fig. 8; Fig. 6 is an enlarged section on line 6 of Fig. 1, Fig. 7 or Fig. 8; Fig. 7 is a section on line 7, Fig. 4; Fig. 8 is a section on line 8, Fig. 6; Fig. 9 is a broken section on line 9, Fig. 8; Fig. 10 is a bottom plan 35 view of a rotatable valve, one of these valves being used for each cylinder of the device; Fig. 11 is a broken perspective view of the valve-operating headed stem; Fig. 12 is a section on line 12, Fig. 1, Fig. 4 or Fig. 19; Fig. 13 is a section taken on line 13, Fig. 3 and enlarged, or on line 13, Fig. 19; Fig. 40 14 is a broken section on line 14, Fig. 13; Fig. 15 is a face view of the cam-headed member of a valve-device, and Fig. 16 is a 45 view of the same in side elevation; Fig. 17 is a face view of the head of the other member of said valve-device and Fig. 18 is a view of the same in side elevation; Fig. 19 is a section on the irregular line 19, Fig. 13, 50 and Fig. 20 is a broken plan view of a clutch-device for reversing the operation of the engine from that of a pump to that of a motor, or vice versa.

A convertible motor and pump, denoted A, as a whole, is shown to comprise four 55 upright cylinders containing pistons, each having its stem connected with a different crank of a crank-shaft 21. The crank-shaft carries on one end a pinion 22 (Figs. 4 and 12), which meshes with and bears a 2 to 1 60 relation to a gear 23 on a shaft 24; these gears being housed in a suitable casing 25. The shaft 24 carries spiral pinions 26 spaced apart to mesh with similar pinions 27 on the lower ends of vertical valve-stems 28 supported to be rotated axially in their bearings in the cylinder-walls, and each terminating at its upper end in a key-like head 29 (Fig. 11). On the top of each cylinder is formed an annular flange 30, these flanges being 70 crossed by an air-passage 31 provided near one end with a port 31^a (Fig. 8). Each flange 30 is formed about a valve-seat containing a port 32 (Fig. 9) leading to the adjacent cylinder and covered by a disk- 75 valve 33 mounted on the seat, against which it is confined to permit it to be turned by a spring-pressed ball 34 bearing centrally against its upper face, in a plug 35 screwed into the annular flange. This valve contains in its under face a recess 33^a forming 80 a port having flaring ends and a circular center, at opposite points of which are slots 29' to receive the head 29 of a stem 28; and diametrically-opposite ports 33^b extend 85 through the valve.

An air-passage 36 is formed in the casting which embodies the cylinders, to extend across the series of valve-stems 28, and is open to the atmosphere at one end and 90 closed at its opposite end (Fig. 7). In one position of any valve 33, as shown in Fig. 9, it opens communication between the passage 36 and the cylinder to which it belongs through a chamber 37 about the upper reduced section of the valve-stem above a seating collar 28^a thereon, thence through the port 33^a in the bottom of the valve and through the port 32; and when, in rotating the valve, a port 33^b therein registers with a 95 port 32, it opens communication through the passage 31 and port 31^a.

The casting containing the cylinders has formed on one end, as an integral part thereof, a sleeve 38 terminating in an enlargement or head 38^a and containing a trans-

verse-recess 38^b. This head has bolted to it a cap 39 formed with an approximately V-shaped extension 40 (Fig. 14) containing in its apex a chamber 40^a and having fastened in one leg a pipe 41 leading to a compressed-air tank 42 (Fig. 1) and in its other leg a pipe 43 leading to a pressure-gage (not shown). The extension of the cap 39 is formed with a disk-head 44. Another casting 45 is formed with a sleeve-section 45^a, a chambered face 45^b co-operating with a similar face opposing it on the disk 44, to confine, between them, a flexible diaphragm 46, centrally against the outer surface of which bears a head 47 on a spring-pressed stem (Fig. 13) working in a lateral socket 48 extending from the sleeve 45^a and mounted on the reduced eccentric end 49^a of a shaft 49 rotatably supported in the sleeve. This diaphragm-including mechanism forms part of the means for producing the automatic operation of my device as herein-after described.

The cap 39 contains a spring-pressed reciprocating hollow-faced valve 50 seating against a nut-confined collar 50^a (Fig. 13), through which works the hollow stem 51 of a disk-shaped valve-head 52 having a transverse groove 53 of arc-shape in cross-section in its face and containing a port 54; and the hollow stem 51 contains elongated slots 55 in its outer end and opposite ports 56, adjacent to the head. A disk-head 57 provided with a convex protuberance forming a cam 58 on its face and fitting in the groove 53 when coincident therewith, is on one section of a shaft 59; and this head contains two similar ports 60. This shaft-section is engaged at a slot in its rear end by a tongue on the forward end of its companion shaft-section, the shaft formed of these two sections being rotatably confined in the sleeve 38 and stably guided in its rotation by a collar 61 fitting in the sleeve-recess 38^b and pinned to the shaft.

On the projecting end of the shaft 59 is secured a crank 62, with which is connected an operating rod 63 working through the inclined foot-board 64 (Fig. 1) of an automobile, or the like (not shown) adjacent to the driver's seat and provided with a knob 65 or handle on its outer end.

Only the shaft 66 of an internal-combustion engine is shown herein (Fig. 20). It carries a gear wheel 67 and a pinion 68. The gear 67 meshes with a pinion 69 loose on the adjacent end of the crank-shaft 21, another loose pinion 70 on which meshes with the pinion 68 through the medium of an interposed idler 71. On the opposing faces of the pinions 69 and 70 are members of a clutch-device 72, the central shifting member of which, on and turning with the crank-shaft, is surrounded by a collar 73 connected by a rod 73^a with the crank 59.

On an end of the shaft 49 is pivoted a crank 74 having a stud 75 working in a yoke 76' on the end of an arm 76 pivotally connected with the crank 62. A link 77 connects the crank 74 with a screw-bolt 78 (Fig. 1) on the cylinder-body through the medium of a spiral spring 79, the tension of which may be adjusted by turning the bolt. These elements form parts of the mechanism for producing the automatic operation referred to.

The operation is as follows: With the knob 65 in the position shown by its full-line representation in Fig. 1, which is its idle or normal position, the cylinder and piston device is idle, not operating either as a motor for starting the internal-combustion engine or as a pump for compressing air into the holder 42 for use in starting the engine. Then the valve 50 is closed. Supposing the internal-combustion engine to be running and the compressed air tank to be empty, the cylinder and piston device is actuated as a pump to compress air into the tank. This results from pulling outwardly the rod 63 to the outermost position in which the knob 65 is shown by dotted representation. Thus the clutch-member 72 is moved to clutch the engine-shaft 66 through the medium of the pinions 68, 71 and 70 to the crank-shaft 21 to rotate the latter to actuate the pistons and rotate the valve-stems 28. At the same time the withdrawal of the rod 63 turns the crank 62, with the effect of turning the shaft 59 sufficiently to cause, by the engagement of the cam 58 with the head 52, the hollow stem 51 to be advanced against the valve 50 and force the latter from its seat against the resistance of the spring behind it. This action opens communication between the cylinders and the tank 42 to cause the pistons, in being driven by the engine-shaft 66, to operate as a pump, while the crank-shaft is continuously rotating the valves 33. The suction-action of the cylinders is exerted through the passage 36, chambers 37, valve-ports 33^a and ports 32 into the upper ends of the cylinders. It should be understood, in this connection, that the rotation of each valve 33 is so timed relatively to the downstroke of the piston to which it relates, as to cause the valve-port 33^a to connect an adjacent chamber 37 and port 32 when the piston is at the upper end of its upstroke, and a port 33^b to register with a port 32 when the respective piston is at the lower end of its downstroke to compress the air by its upstroke. Air thus sucked into each cylinder is compressed by the upstroke of its piston through a port 32, valve-port 33^b, passage 31, port 31^a, a port 60 in the head 57 then registering with a port 54 in the head 52, thence into the chamber 56, through the holes 56 in the hollow stem 51 and the slots 130

55 in the latter past the valve 50 into the chamber 40^a and by way of the pipe 41 into the tank.

With the tank charged with air under 5 pressure and the internal-combustion engine out of operation, to use my improvement as a motor for starting the engine, the rod 63 is pressed inwardly to bring the knob 65 to the innermost dotted position represented 10 in Fig. 1, whereby the rod 73^a ships the clutch to gear the crank-shaft to the engine-shaft 66. This setting of the rod 63 opens the tank 42 through the chamber 40^a, past the valve 50, through the stem-slots 55, holding 15 low stem 51 and holes 56 into the chamber 56^a in head 38^a, thence through the hole 54 in head 52, a hole 60 in head 57 then registering therewith, ports 31^a and the passage 31 through the valve-ports 33^b and ports 32 20 into the cylinders. As will be understood in this connection, timing of the parts referred to is such as to open a port 33^b in the rotation of each valve 33 by the crank-shaft to the respective cylinder when the piston 25 therein is at the upper end of its upstroke, and to register a recess 33^a in a valve with an adjacent-port 32 when the piston is at the lower end of its downstroke, thus to cause its upstroke to exhaust the pressure 30 through the pipe 36 from a port 32, through the valve-recess 33^a and chamber 37; the rotation of the valves 33 being produced by the gear-connections 27, 26, 23 and 22 of their stems with the crank-shaft. The cam- 35 valve in the sleeve 38 serves to prevent leakage from the chamber 56^a along the shaft 59.

When the tank 42 contains compressed air, its pressure is exerted with adequate 40 force against the inner face of the diaphragm 46, which is always open to the tank through the chamber 40^a, to overcome the force of the spring pressing against the head 47 (Fig. 13) mounted on the eccentric 45 end of the shaft 49. This is the condition of the parts when the internal-combustion engine is running and out of clutch with the crank-shaft 21. Should the pressure fall in the tank, due to leakage or exhaustion, 50 below that of the spring-pressure against the diaphragm, the spring will act to turn the shaft 49, thereby turning the crank 77 against the resistance of the spring 79. When the crank 75 reaches the end of the 55 slot 76' (Fig. 1) the spring-connection 77 with the crank has passed the dead-center and the recoil of the spring, in further turning that crank, causes its connection with the latter to correspondingly turn the crank 60 62, with the effect of actuating the rod 73^a to clutch the engine-shaft to the crank-shaft and work the pistons in the cylinders as a pump. The further effect of thus turning the crank 62 is to actuate the shaft 59 to 65 unseat the valve 50 in the way already de-

scribed, with resultant opening of communication between the outer air, through the passage 36, and the tank 42. When the air-pressure thus automatically introduced into the tank attains the predetermined degree, 70 to prevent excess thereof, which might burst the tank, the pressure against the diaphragm from the chamber 40^a turns the shaft 49, thereby overcoming the spring-resistance against the head 47 and turning the crank 75. 74 in the opposite direction until its pin reaches the inner end of the slot 76', when the spring 79 will act to snap that crank back to normal position, and the arm 76 will actuate the crank 62 to its normal position, 80 thereby unclutching the crank-shaft from the shaft 66 and turning the shaft 59 in the direction to permit re-seating of the valve 50.

I realize that considerable variation is possible in the details of construction thus 85 specifically shown and described, and I do not intend by illustrating a single, specific or preferred embodiment of my invention to be limited thereto, my intention being in the following claims to claim protection 90 for all the novelty there may be in my invention as broadly as the state of the art will permit.

What I claim as new and desire to secure 95 by Letters Patent is:

1. A pneumatic starter for an internal-combustion engine, comprising, in combination with an air-pressure storage-tank, a convertible pump and motor device communicating with said tank and the outer air 100 and provided with means for connecting it with and disconnecting it from the engine-shaft, a spring-seated valve normally closing the communication, co-operating valve-members and a rotary shaft carrying one of 105 said members operated by turning the shaft to open the spring-closed valve, an operating rod connected with said shaft for turning it, and a valve in the communication connected with said device to be moved 110 thereby and containing ports connecting, in the movement of the valve, said device alternately with the outer air and said tank.

2. In a pneumatic starter for an internal-combustion engine, having an air-pressure 115 storage-tank, a convertible pump and motor device communicating with said tank and the outer air and provided with means for connecting it with and disconnecting it from the engine-shaft, and a valve in the communication connected with said device to be moved thereby and containing ports connecting, in the movement of the valve, said device alternately with the outer air and 120 said tank, a headed sleeve in said communication, a spring-seated valve in the head, a valve-member reciprocably confined in the head and having a recessed head and a hollow stem to bear against the spring-pressed 125 valve, a rotary shaft in the sleeve having a 130

cam-faced valve-member on its inner end to coöperate with said recessed head and actuate said first-named valve member, and an operating rod connected with said shaft for 5 turning it, for the purpose set forth.

3. In a pneumatic starter for an internal-combustion engine, having an air-pressure storage-tank, a convertible pump and motor device communicating with said tank and 10 the outer air and provided with means for connecting it with and disconnecting it from the engine-shaft, and a valve in the communication connected with said device to be moved thereby and containing ports connecting, in the movement of the valve, said device alternately with the outer air and 15 said tank, a headed sleeve in said communication, a spring-seated valve in the head, a valve-member reciprocably confined in the head and having a recessed head and a hollow port-containing stem to bear against 20 the spring-pressed valve, a rotary shaft in the sleeve having a cam-faced valve-member loosely connected with its inner end to seat 25 against the rear wall of the head and co-operate with said recessed head to actuate said first-named valve-member, and an operating rod having a crank-connection with 30 said shaft for turning it, for the purpose set forth.

4. In a pneumatic starter for an internal-combustion engine, the combination with an air-pressure storage-tank, of a convertible pump and motor comprising a plurality of 35 piston-containing cylinders intercommunicating through a port-containing passage through which they communicate with said tank, and a crank-shaft for the pistons, provided with means for connecting it with and 40 disconnecting it from the engine-shaft, a passage open to the outer air communicating through ports with the cylinders, rotary valves mounted between said passages on stems geared to the crank-shaft, each valve 45 containing ports connecting, in its rotation, a cylinder alternately with said outer-air passage and said other passage, a spring-pressed valve normally closing communication between said tank and said last-named 50 passage, and an operating rod having connections with said spring-pressed valve for unseating it and with said means for connecting the crank-shaft with and disconnecting it from the engine-shaft.

55 5. In a pneumatic starter for an internal-

combustion engine, the combination with an air-pressure storage-tank, of a convertible pump and motor comprising a plurality of piston-containing cylinders intercommunicating through a port-containing passage 60 through which they communicate with said tank, and a crank-shaft for the pistons, a passage open to the outer air communicating through ports with the cylinders, rotary valves mounted between said passages on 65 stems geared to the crank-shaft, each valve containing ports connecting, in its rotation, a cylinder alternately with said outer-air passage and said other passage, a sleeve having a hollow cap-covered head with which 70 the storage-tank is connected, a spring-seated valve in the cap, a rotary shaft in the sleeve and means therein operated by turning the shaft to open the spring-seated valve, a crank on said shaft, an operating 75 rod connected with said crank, a clutch-device for connecting and disconnecting the crank-shaft and engine-shaft, and a rod connecting said crank with said device for shipping and unshipping the clutch by the 80 operating rod.

6. In a pneumatic starter for an internal-combustion engine, the combination of an air-pressure storage tank, a valved convertible pump and motor communicating with 85 said tank and the outer air and provided with means for connecting it with and disconnecting it from the engine-shaft, a sleeve in the communication to which said tank is connected and containing a rotary shaft and 90 valve-mechanism operated by the sleeve to open and close said communication, a crank on the sleeve connected with said connecting and disconnecting means and having an operating rod connected with it, a flexible 95 diaphragm having one surface open to said tank, a second sleeve containing a rotary shaft having mounted eccentrically thereon a spring-pressed head bearing against the opposite diaphragm-surface, a spring- 100 thrown crank on the last-named shaft, and an arm provided with a loop and connecting the two cranks, for the purpose set forth.

In testimony whereof I have hereunto set my hand this 31st day of January, 1914. 105

GEORGE A. GEMMER.

In presence of two subscribing witnesses—

A. C. FISCHER,

F. A. FLORELL.
